Design for the Accordion.

The schedule referred to in these letters will stand making part of the same.

To all it bore it may concern:

But know that I, Cemetery of the City and County of New York, have invented a new and improved design for the Ace of Spades; and I do hereby declare that the following description, taken in connection with the accompanying drawing is a full, clear and exact specification thereof, which will enable others skilled in the art to make and use the same.

The present invention relates to a new and improved design for the ace of spades in a pack of playing cards, which design is illustrated in the accompanying plate, and consists of the usual representation of the ace, in the said plate, above which, upon its right and left, is represented the head and shoulders, respectively, of George Washington, and on the Hutchinson, with each picture being produced upon a ground which is of a uniform size and color.

The emblem of the national shield of this country, located near the top, is a large picture of George and Martha Washington, between them are some ground works upon the upper side of a ledge of rock. A bird is represented as perched on an American Eagle, with its wings out spread, it is seated on a rock in one claw and a branch of laurel in the other, as a crest it is grasped by its beak, hanging in

feats and drooping across the face of the card, with its initial letters
about the oval ground work of the card. On this scroll "Chant Heart
#6" is indicated in letters in "Philadelphia and New York" and a pencil
at the bottom of the card, goes below the ace of spades. A

Crease angle extending in a circular direction in
pines of the tree, or star for the thirteen original states of the country.

The use of pines is surrounded by a scroll of pine
leaves and branches of the oval ground in the Martha and George

Washington, just below inscribing the name of the First Bank of March.

The various parts of the design having the distinctive
features hereinabove described, it is intended to have colored with proper
undevatable colors, and stain, which when combined will produce a
beautiful, neat, tasteful and elegant finish and facets to card.

First claim as new and due to issue by Patent Office
Design of the "ace of spades" to be registered
described:
